UNITED STATES PATENT OFFICE

128,186

DESIGN FOR A CAKE KNIFE OR ANALOGOUS ARTICLE

Morris Yellin, Chicago, Ill., assignor to Nu-Dell
Manufacturing Company, a corporation of Illinois

Application May 23, 1941, Serial No. 101,106

Term of patent 3½ years

To all whom it may concern:

Be it known that I, Morris Yellin, a citizen of the United States, residing at Chicago, in the county of Cook and State of Illinois, have invented a new, original, and ornamental Design for a Cake Knife or Analogous Article, of which the following is a specification, reference being had to the accompanying drawing, forming a part thereof.

In the drawing:

Fig. 1 is a front elevational view of a cake knife showing my new design;

Fig. 2 is a plan view thereof; and

Fig. 3 is a sectional view through the blade taken on the line 3—3 of Fig. 1.

I claim:

The ornamental design for a cake knife or analogous article, as shown.

MORRIS YELLIN.
